TACK MACHINE

Edward C. Baker and Delbert W. Manson, Brockton, Mass., assignors, by direct and mesne assignments, to D. B. Gurney Company, Whitman, Mass., a corporation of Massachusetts

Application July 25, 1936, Serial No. 92,584

14 Claims. (Cl. 10—173)

This invention pertains to machines for making cut tacks or nails, and relates more particularly to improvements in mechanism for feeding and presenting the tack strip to the cutter,—the 5 present invention constituting an improvement upon that disclosed in the patents to Baker et al., No. 1,555,933, dated October 6, 1925 and No. 1,864,267, dated June 21, 1932.

One principal object of the present invention 10 is to provide strip feeding means of improved type designed to present the end of the tack strip to the cutter with such accuracy as to permit the cutting of tacks having very fine and accurately shaped points, for example, shoe tacks, 15 and to this end the improved mechanism comprises means for positively advancing the tack strip toward the cutters having provision for accurate adjustment of the timing of the advance movement of the strip relatively to the 20 working stroke of the cutters.

A further object is to provide strip advancing means which receives its movement directly from the main shaft of the machine thereby to insure proper timing, but so devised as not to obstruct 25 the tack maker in his duties in adjusting or replacing the cutters, etc.

A further object is to provide for both a coarse 30 and a fine adjustment of the strip feed, with provision for making such adjustments without interference with other settings of the mechanism.

A further object is to provide means for retracting the tack strip from the path of the cutter as the latter rises, thereby to avoid dulling 35 the cutters by contact of the upwardly moving cutters with the end of the tack strip.

A further object is to provide an improved 40 support or bearing for the strip guiding barrel,—to provide a readily removable saddle for retaining the barrel in operative position; to provide an improved tension for the feed rolls; to provide an improved nose piece such as to expose the tack strip freely to view as it approaches the cutter, 45 and so devised that it will not readily become clogged with accumulations of lime from the strip; and to provide a simple and effective signal to show when the strip needs replenishment.

Further objects and advantages of the invention 50 will be made apparent in the following more detailed description and by reference to the appended drawings wherein

Fig. 1 is a fragmentary side elevation of the improved feed mechanism, together with so much 55 of a usual type of tack machine as is necessary

to indicate the relationship of the new mechanism thereto;

Fig. 2 is a fragmentary front view, to smaller scale, showing the upper part of the tack machine and illustrating the novel mechanism for actuating the tack strip feed; 5

Fig. 3 is a fragmentary side elevation, to larger scale, showing details of the feed mechanism of Fig. 1;

Fig. 4 is a fragmentary vertical section to 10 larger scale, substantially on the line 4—4 of Fig. 3, showing details of the improved barrel-retaining saddle;

Fig. 5 is an elevation to large scale showing the saddle-retaining pin removed from the saddle; 15

Fig. 6 is a bottom view of the pin of Fig. 5;

Fig. 7 is a fragmentary bottom view of the saddle of Fig. 4 showing the means for holding the pin in operative position; 20

Fig. 8 is a fragmentary plan view showing the saddle and a part of the barrel and adjacent elements;

Fig. 9 is a fragmentary plan view showing the means for retracting the barrel after each cutting operation; 25

Fig. 10 is a fragmentary vertical section substantially on the line 10—10 of Fig. 9;

Fig. 11 is a developed view of the barrel-retracting cam illustrated in Figs. 9 and 10; 30

Fig. 12 is a fragmentary plan view of the delivery end of the barrel with its attached nose piece,—the feed roll housing, and the means for driving the feed rolls;

Fig. 13 is a vertical section substantially on the line 13—13 of Fig. 12; 35

Fig. 14 is a vertical section substantially on the line 14—14 of Fig. 12;

Fig. 15 is a fragmentary perspective view with the several associated parts separated from each other, showing details of the feed roll loading devices and illustrating an upper feed roll of a modified type; 40

Fig. 16 is a perspective view to large scale illustrating a part of the mechanism for driving the feed rolls; 45

Fig. 17 is a fragmentary longitudinal section showing one end of the eccentric rod with its adjustable snap connection;

Fig. 18 is a plan view of one desirable form of nose piece, shown as removed from the barrel; 50

Fig. 19 is an edge elevation of the nose piece of Fig. 18; 55

Fig. 20 is a plan view of a modified form of nose piece;

Fig. 21 is an edge elevation of the nose piece of Fig. 19;

Fig. 22 is a fragmentary plan view of a signal device operative to show when the tack strip needs replenishment;

Fig. 23 is a fragmentary elevation, partly in vertical section and to larger scale, illustrating a preferred and modified feed actuating mechanism;

Fig. 24 is a section on the line 24—24 of Fig. 23; and

Fig. 25 is a detail view, in perspective, of one element of the mechanism of Figs. 23 and 24.

Referring to the drawings, the numeral 1 designates the main frame of a tack or nail machine of a usual type, such machine having the main drive shaft 2 provided at one end with a hand wheel 3 (Fig. 2) and with a drive pulley 4. The machine frame also supports the fixed anvil block 5 (Fig. 3) which carries the stationary or ledger blade 6 with which cooperate the cutters 7 and 8, which, together with the forming tools 9 and other adjunctive features common to the art, receive their motion through suitable connections actuated by the main shaft 2.

The frame also comprises the forwardly extending supporting arm 9 which carries appropriate bearings in which oscillates the hollow barrel 10 which receives and guides the tack strip on its way to the cutters. This barrel is oscillated by means of a pair of oppositely wound straps 11 and 12 which are pulled downward alternately by appropriate mechanism, not shown, common in the art. As here illustrated, the machine is provided with a stand 13 which supports a reel 14 upon which is wound a coil of tack strip 15, the strip entering the left-hand end of the barrel, as viewed in Fig. 1, and moving longitudinally of the barrel toward the right-hand or delivery end of the latter.

The frame member 9 carries the upstanding stationary bracket 16 which in accordance with the present invention is provided with a bearing for a swivel member 17 having a vertical spindle 18 turning in a socket in the bracket 16. This swivel member 17 supports a ball bearing 19 within which the barrel 10 is free to turn and also to slide axially. A coiled spring 20 encircles the barrel, bearing at one end against the housing of the ball bearing 19 and at its other against a collar 21 fixed to the barrel,—the spring thus tending to move the barrel longitudinally toward the cutters.

In accordance with the present invention, the barrel is provided with a collar having a radial cam flange 22 (Figs. 1, 9, and 10) such cam flange having two substantially radial dwell portions 23 at diametrically opposite points, such dwell points being separated by the bosses 24. This cam flange cooperates with a roller 25 turning on a vertical stub shaft 26 projecting upwardly from a bracket 27 fixed to the frame member 9. The spring 20 urges the barrel 10 to the right, as viewed in Fig. 1, and thus tends to keep the cam flange 22 always in contact with the roller 25. The radial dwells 23 and the bosses 24 are so arranged that upon each oscillation of the barrel, whether in one direction or the other, the barrel will be bodily retracted away from the cutters in an axial direction immediately upon completion of each down stroke of the cutters, and while the cutters are on their upward or retracting stroke, so as to keep the

end of the tack strip out of contact with the cutters as they retract, thus avoiding unnecessary dulling of the cutters.

The frame member 9 also supports a bracket 27^a which carries a laterally directed arm 28 (Fig. 4) having an upstanding ear 28^a near its free end. This ear provides bearings for a pin 29 whose axis is substantially parallel to that of the barrel and which supports a vertically swinging saddle arm 30 to the free end of which is secured a bearing member 31 which normally rests upon the upper part of the barrel 10. This member 31 may be of any suitable material, preferably of a type which will form a good bearing contact with the barrel. This bearing member is urged downwardly against the barrel by means of a coiled compression spring 32, the upper end of which bears against a collar 33 adjustably fixed to a retaining pin 34. This pin is furnished with a handle 35 at its upper end and passes freely down through an opening in the arm 30. The lower end of this pin 34 is furnished with a transverse locking element 36 (Fig. 6), and the bracket arm 28 is furnished with an elongate slot 37 (Fig. 7) through which this member 36 may be passed when disposed in registry with the slot. However, after the member 36 has been passed through the slot 37, a quarter turn of the pin 34 will dispose the member 36 out of registry with the slot 37 and below the lower surface of the bracket, as shown in Fig. 7, so that the pin is locked in position with the spring 32 holding the saddle or bearing member 31 in resilient contact with the barrel. This arrangement provides for holding the delivery end of the barrel downwardly so as to keep the end of the tack strip in contact with the ledger blade 6, although permitting the barrel to rise as it oscillates and the tack strip turns about its narrow edge from one side to the other. Furthermore, merely by depressing the pin 34 and turning it a quarter turn, it is possible to release the saddle 31 from the barrel, whereupon the entire saddle device including the arm 30 may be swung about the pin 29 and away from the barrel, thus leaving the operator free to make such adjustments in the barrel or the feed mechanism as may be requisite.

To the right of the saddle device just described, as viewed in Figs. 1 and 2, the barrel is provided with a drive actuating sleeve 38 (Fig. 16) arranged to slide freely on the barrel and having a downwardly directed pin 39 which moves freely in a slot 40 in an arm 41 (Figs. 1 and 8) fixed to the bracket 27^a. This actuator sleeve 38 comprises a radial flange member 42 and at its left-hand side, as viewed in Figs. 1, 3, and 16, with a block 43 having an upstanding stem 44 provided at its upper end with a substantially spherical knob 45 forming one element of a snap fastener.

Referring to Figs. 1, 2, and 3, the main frame of the machine is provided with bearings 46, 46^a for a secondary shaft 47 preferably parallel to the drive shaft 2 and provided with a gear 47^a which meshes with a gear 48 on the shaft 2 so that the shaft 47 always turns in substantially exact consonance with the shaft 2. Preferably the upper bearings 46 are removable at will, so that the shaft 47, with the parts fixed to it, as hereafter described, may be lifted from its bearings, turned in one direction or the other, and replaced, so as to cause different teeth of gear 47^a to mesh with gear 48. This relative shifting of the gears provides for a coarse adjustment

of the feed roll drive, as hereinafter more fully described.

The shaft 47 is provided with an eccentric 49 or equivalent element, here shown as provided with a split bushing 49^a which, together with a fork member 49^b, constitutes the eccentric strap. The fork member is provided with diametrically opposite adjusting screws 50 which bear upon the bushing 49^a and which permit the effective eccentricity of the member 49 to be varied to some extent as well as providing for taking up wear in the bushing and to allow some freedom of pivotal movement in a transverse direction to the eccentric rod. The fork member 49^b has connected thereto one end of the eccentric rod 51, the latter preferably having screw threads 52 at its upper end whereby it may be adjusted relatively to the yoke or fork member, thus permitting a fine adjustment of the roll driving devices.

At its opposite end the eccentric rod 51 is provided with a sleeve member 53 (Fig. 17) which may, if desired, be adjustable longitudinally of the rod, as for example by means of screw threads and a lock nut,—the sleeve 53 being closed at its end 54 and having within it a sliding plug 55 whose left-hand end, as here illustrated, (Fig. 17) is furnished with a spherically curved socket. This plug 55 is urged toward the closed end of the sleeve by means of a spring 56, one of which bears on the plug and the other against the end of the rod 51. Near its closed end the sleeve 53 is furnished with an opening 57 in its wall, of such size as to permit the ball or knob 45 of the member 42 to be snapped into the interior of the sleeve 53 where it is engaged by the plug 55, the latter first retracting against the spring 56 and then snapping back into engagement with the knob 45, thereby to provide an operative connection between the rod 51 and the part 52, so that the latter is constrained to move longitudinally of the barrel in time with the rotation of the shaft 47. However, if it be desired to disconnect the rod 51, it is merely necessary to lift the sleeve 53 with sufficient force to disengage the ball 45 from its socket 57, whereupon the rod 51 may be swung upwardly, as shown in broken lines in Fig. 1, and out of the way so that it will not interfere with the work of the tack maker in adjusting or resetting the tack-making tools.

Referring to Figs. 12 to 14 inclusive, the delivery end of the barrel is shown as provided with a feed roll housing 58 having bearings for the shaft 59 of a bottom feed roll 60, which, as illustrated in Fig. 14, has a substantially flat peripheral work-contacting surface. The shaft 59 extends outwardly at both sides of the housing member 58, being provided at one end with a gear 61 and at its opposite end with a ratchet wheel 62. This ratchet wheel projects up into a slot in a longitudinally movable pawl-carrying bar 63 which is mounted to slide in bearings in bracket members 64 and 65 projecting from the side of the housing 58. This pawl-carrying bar 63 is urged to the left, as viewed in Fig. 12, by a spring 66 which is secured at one end to the bracket 65 and at its other end to a pin 67 projecting from the bar 63. The bar 63 carries a resilient pawl member 68 which engages the teeth of the ratchet 62, being so arranged that on movement of the bar 63 to the right, as viewed in Fig. 12, the ratchet wheel and the shaft 59, together with the feed roll 60, is turned in a clockwise direction, as viewed in Fig. 13.

The bar 63 also carries a roll 69 which is held

in contact with the right-hand face of the flange 42 of the actuating device by the action of the spring 66. Thus, as the actuating device 38 is reciprocated along the barrel 10 by the eccentric 49, the bar 63 is also reciprocated and at each movement toward the right (Fig. 12) turns the feed roll 60 through a part revolution, the distance through which the roll turns being determined by the effective eccentricity of the member 49. It will be noted that the forward stroke of the pawl is a positive movement, there being no yield between the eccentric and the parts driven thereby, so that the advance of the tack strip is a positive advance and may be gauged with the greatest nicety, with respect to the operation of the cutting and forming devices, by the setting of the gears 47^a and 48 relatively to each other, and by the adjustment of the rod 51 relatively to the yoke 49.

The upper feed roll 70, which in Fig. 14 is shown as having an edge or peripheral surface of substantially V-cross section so as to provide a narrow edge for engagement with the tack strip (this being especially desirable when using a tack strip which is of soft material) is carried by a shaft 71 having bearings preferably mounted in vertical slots 72 in the side walls 58^a and 58^b (Fig. 15) of the feed roll housing. The shaft 71 is provided with a gear 61^a which meshes with gear 61. These slots 72 receive bearings 73 which, as illustrated in Fig. 15, are furnished with recesses 74 designed to fit over the edges of the slots 72 so that the bearings 73 may slide freely in a vertical direction but without turning in the slots 72. As shown in Fig. 15, the peripheral edge of the feed roll 70^a is flat like that of the bottom feed roll 60, although the V-edge top roll, previously described, is preferred.

In order to press the top feed roll downwardly against the tack strip with resilient pressure so as to insure a proper feed of the strip, it is preferable to provide a rocker device such as shown in Figs. 12 to 15. This rocker device is of substantially T-shape, having the transverse crossbar 75 and the stem portion 76. The member 75 is furnished with a slot 75^a for the reception of the edge of the upper feed roll, and the member 76 is preferably formed of a length of wire bent to form a curved or rounded end 77 and having its extremities secured in the bar 75. By thus making the member 76, a longitudinal slot 81 is provided appropriate to receive a pin 82 (Fig. 13) having a screw-threaded engagement with the upper part of the housing 58. A coiled spring 83 surrounds this pin and bears at its lower end on a washer 84 bridging the slot 81 and resting upon the arms of the member 76. The upper end of the spring bears against a wing nut 85 at the upper end of the rod 82. The curved or rounded end 77 of the member 76 rests upon the upper surface 78 of the housing 58, while the opposite end portions 79 and 80 of the bar 75 rest upon the respective bearing members 73. The rocker device as a whole may be moved longitudinally with reference to the pin 82 thereby to dispose it in the most effective position for applying the tensioning pressure to the bearings 73 and since it is free to rock about the rounded end 77 (having in effect a three point bearing) the two bearing members 73 are permitted to rise and fall more or less independently so as to insure maintenance of proper pressure between the upper and lower feed rolls, even though one or the other of the bearings 73 should not work as freely as intended, as, for example, by reason of accumulation of

dust or dirt between it and the edges of the slots 12.

Near its right-hand end the housing 58 is provided with a transverse shaft or pivot pin 87 upon which is mounted a nose piece support 86. This nose piece support is provided at opposite sides with upstanding ears 88 and 89 (Fig. 12) having threaded openings for a pair of aligned oppositely directed adjusting screws 90 and 91, respectively. Near the end of the barrel 10 the housing 58 is also furnished with two pairs of vertically aligned adjusting screws 93 and 94.

The preferred form of nose piece as here illustrated (Figs. 18 and 19) comprises an elongate plate 95 having a downwardly directed stud 96 which is adapted to enter an elongate slot 92 (Fig. 12) in the nose piece support 86 and to be disposed between the ends of the screws 90 and 91.

The plate 95 has a substantially flat upper surface 20 but is furnished at its left-hand end, as indicated in Figs. 18 and 19, with an integral bridge member 97 having a horizontal slot 98 adapted to receive and to guide the tack strip as the latter is delivered from the barrel proper and 25 enters the feed roll housing.

The nose piece is provided with a slot 100 through which the upper part of the lower feed 30 projects, and where the nose piece projects beyond the housing it is furnished with one or more openings 101 designed to permit any lime carried by the tack strip and which may be separated from the latter as the strip passes through the nose piece, to escape freely so as not to clog the nose piece. By adjustment of screws 90 and 35 91 the end of the nose piece may be swung horizontally, and by adjustment of screws 93 and 94 the end of the nose piece may be swung vertically.

In order to hold the tack strip down in proper 40 position on the nose piece as it traverses the latter, it is preferred to provide a pivot pin 105 projecting upwardly from the nose piece at one side of the path of movement of the tack strip and to mount on this pin a resilient leaf-spring hold-down arm 104 preferably provided at its free 45 end with an opening 106 designed to be snapped over a pin 107 at the other side of the nose piece and diagonally disposed with respect to the pin 105.

The delivery end of the nose piece is preferably 50 furnished with an integral bridge member 102 having an elongate slot 103 for guiding and directing the tack strip as the latter approaches the cutters.

Normally the hold-down arm 104 occupies the 55 full line position of Fig. 18, thus overlying the tack strip which extends from the guide opening 98 to the guide opening 103 and which is confined and held against the upper surface of the plate 95 by the resilient hold-down arm. However, to facilitate introduction of a new tack 60 strip or to permit inspection or cleaning of the nose piece it is possible, by lifting the free end of the hold-down arm from the pin 107, to swing the hold-down arm about the pivot 105 to the 65 broken line position of Fig. 18 where it no longer overlies the nose piece, thus permitting free inspection of and access to the tack strip and nose piece.

In Figs. 20 and 21 a modified form of nose piece 70 is shown, this nose piece comprising the elongate plate member 95^a having at one end the integral bridge piece 97^a furnished with the guide opening 98^a and provided at its opposite end with the integral bridge piece 102^a having the guide opening 103^a. In this instance the upper surface of

the nose piece is preferably provided with an elongate shallow recess 101^a to reduce friction of the tack strip against the surface of the nose piece and also to provide clearance for any lime which may fall from the tack strip on its way through the nose piece. In this arrangement, in place of the resilient hold-down arm 104, there is provided a rigid hold-down member or bridge piece 104^a having a guide opening 105^a for the tack strip and provided at its sides with lugs furnished with screw-threaded openings 104^b for the reception of set screws by means of which it may be held in adjusted position longitudinally of the nose piece. Such adjustment may be desirable in dealing with tack strips of different thickness 15 or width or of different materials, and enables the tack maker to locate this intermediate control of the tack strip at any desired point between that shown in Fig. 20 and the left-hand end of the fixed bridge member 102^a. 20

In order to indicate to the operator of the machine that it is time to replenish the tack strip, it is preferred to provide a signal device such as illustrated, for example, in Figs. 1 and 22. This signal device comprises a bracket 106 (Fig. 22) 25 carried by the member 9 or other convenient part and furnished with a stub shaft 107 on which is mounted a lever 108 arranged to swing in a vertical plane. At one end this lever is furnished with a counterbalance weight 109 which is adjustable along the lever to provide for accurate balancing while the other end of the lever is furnished with a transversely extending finger or feeler element 110 which normally underlies the tack strip 15 at a point between the reel 14 and 30 the receiving end of the barrel 10. So long as the tack strip continues to move from the reel to the barrel it holds down the finger 110 in opposition to the action of the weight 109, but as soon as the end of the coil of tack strip passes the 35 finger 110, the weight 109 swings the lever 108 up to a more or less vertical position, as shown in broken lines in Fig. 1. In order to make this movement of the lever more clearly evident to the operator, it is preferred to mount a target 40 or flag 111 on the lever so that such target or flag will be raised as the lever swings and thus become readily visible to the operator from a substantial distance.

Under certain circumstances, particularly in 50 the larger machines, it has been observed that the angularity of the rod 51 tends to lift the barrel during the feed stroke or movement of the rod to the right, as viewed in Fig. 3. To avoid any possibility of actual lifting of the barrel from 55 this cause, it is preferred to employ a modified construction illustrated by way of example in Figs. 23 to 25 inclusive.

Referring to the latter figures, the numeral 27^a indicates the upper part of the bracket similarly 60 designated in Fig. 1. In this instance the bracket 27^a is provided with a substantially horizontal upper surface upon which rests a plate 112, preferably provided with a central, downwardly directed pin 113 which swivels in a socket 114 65 in the bracket 27^a. The plate 112 is furnished with a pair of spaced openings 115 which receive adjusting bolts 116, the bolts passing loosely through the openings 115 so as to permit a slight adjustment of the plate 112 angularly about the 70 axis of its pin 113, after which the bolts 116 may be tightened to hold the plate in adjusted position.

The plate 112 is provided with an upstanding central boss 112^a (Fig. 23) including a sleeve por- 75

tion 41^a provided with a horizontal bore constituting a guideway for a rod 117. This rod is provided with a fixed collar 117^a at one end. A coil spring 118 embraces the rod and bears at its 5 opposite ends against the collar 117^a and against one end of the sleeve 41^a, respectively. The opposite end of the rod 117 is preferably reduced in diameter and screw threaded for engagement with a screw-threaded bore in a downwardly 10 directed ear 120 forming part of a yoke member 121 (Fig. 24). This yoke member comprises upwardly directed arms 122 and 123 defining between them a recess 124 having substantially parallel side walls and a curved bottom wall 125. 15 The barrel 10 is disposed within this recess,—the recess being of sufficient depth to permit the necessary up-and-down motion of the barrel during the operation of the machine, but being of such width as to keep the barrel accurately positioned horizontally.

15 The barrel 10 is disposed within this recess,—the recess being of sufficient depth to permit the necessary up-and-down motion of the barrel during the operation of the machine, but being of such width as to keep the barrel accurately positioned horizontally.

A bar 126 (Fig. 25) normally closes the upper end of this recess 124, the bar having openings 127 and 128 near its opposite ends. The upper ends of the arms 122 and 123 of the yoke are 20 slotted to receive the end portions of the bar 126 respectively, and are also furnished with screw-threaded openings for the reception respectively of a bolt 129 (which passes through the opening 127 of the bar 126 and constitutes a pivot for the 25 bar) and a wing bolt 130 (which passes through the opening 128 in the bar 126 and normally holds the bar fixed to the yoke). However, by retraction of the wing bolt 130, the bar may be 30 swung to the dotted position shown in Fig. 24 so as to permit the barrel to be lifted from the recess 124.

At its central part the bar 126 is provided with an upwardly inclined neck member 44^a provided at its extremity with a knob or ball 45^a corresponding in function to the knob or ball 45 above described and which is normally received in a 40 socket in the member 53 carried by the rod 51. The latter, as above described, is reciprocated in time with the rotation of the drive shaft of the 45 machine by means of an eccentric, cam, crank or equivalent mechanical device. The yoke 121 corresponds in function to the actuator device 38 above described and is furnished at its left-hand side, as viewed in Fig. 23, with plate 42^a, preferably of hardened steel, which bears against roll 50 69 and performs the same function in this respect as the flange 42 of the actuator above described.

In this construction the yoke or actuator 121 is positively guided in a rectilinear path by means 55 of the sleeve 41^a and rod 117, and whatever upward component of force may be exerted by the reciprocating rod 51, such component is opposed by the guide elements 41^a and 117 so that no lifting effort is applied to the barrel.

60 The general operation of the machine will be obvious, without specific description, to those skilled in the art, it being sufficient to note that the movement of the feed roll actuator 38 has a positive movement in the feed direction and is 65 in substantially exact consonance with the operation of the main drive shaft 2, so that the presentation of the tack strip to the cutters is very accurately controlled, thus making it possible to cut tacks with accurately shaped points 70 such as are requisite for certain uses, particularly in the shoe trade. It is further to be noted, as above pointed out, that this feed movement is capable of both coarse and fine adjustment. Furthermore, since the eccentric rod 51 may so 75 readily be disconnected, the provision of this

improved drive mechanism need not in any way interfere with the usual operations of the tack maker in setting and adjusting the various cutting and forming instruments.

While desirable features of the invention have 5 been herein specifically described, it is to be understood that the invention is not necessarily limited to the details of construction illustrated, but that the invention is capable of embodiment in various other arrangements of parts and that 10 all equivalents and variations falling within the scope of the appended claims are to be regarded as a part of the present invention.

We claim:

1. In combination with a tack or nail machine 15 having a rotary drive shaft, cutters and forming tools, an oscillatory strip-guiding barrel, means for oscillating it, and a pair of strip-feeding rolls mounted on the barrel, a drive element turning in consonance with the drive shaft, a reciprocating 20 rod actuated by said drive element, a roll-driving pawl, a reciprocable, non-oscillatory pawl actuator, guide means comprising a normally fixed part and a relatively sliding part constraining said actuator to move in a predetermined 25 rectilinear path lengthwise of the barrel, and readily disengageable connections between the rod and actuator.

2. In combination with a tack or nail machine 30 having a rotary drive shaft, cutters and forming tools, an oscillatory strip-guiding barrel, means for oscillating it, and a pair of strip-feeding rolls mounted on the barrel, a part moving in consonance with the drive shaft, a reciprocating rod 35 actuated by said moving part, a roll-driving pawl, a pawl actuator reciprocable along the barrel, means whereby the length of the rod may be adjusted, a stem carried by the actuator provided at its end with a spherically curved knob, and a sleeve member carried by the rod having therein 40 a socket for the reception of said knob.

3. In combination with a tack or nail machine having fixed and movable cutters and forming tools and means for actuating them, an oscillatory barrel for guiding tack strip to the cutters, 45 and means for oscillating the barrel, a saddle device for yieldingly retaining the delivery end of the barrel in operative relation to the cutters, said saddle device comprising an arm hinged to turn about an axis substantially parallel to that 50 of the barrel and disposed at one side of the latter, and means yieldingly pressing the free end of the arm downwardly toward the barrel, said pressure-applying means comprising a releasable normally fixed abutment pin, a spring reacting 55 between a portion of the pin and said arm to hold the arm in barrel-retaining position, and releasable means normally holding the pin in operative position but constructed and arranged to permit release of the pin, thereby to allow the 60 arm with the spring to be swung away from the barrel.

4. In combination with a tack or nail machine having fixed and movable cutters and forming tools and means for actuating them, an oscillatory barrel for guiding tack strip to the cutters, and means for oscillating the barrel, hold-down 65 means normally operative yieldingly to retain the delivery end of the barrel in operative relation to the cutters, said hold-down means comprising a barrel-engaging element movable when released to a position wholly at one side of the barrel, said hold-down means comprising an abutment pin having a locking element engaging a fixed part of the frame but releasable therefrom 70 75

by partial rotation of the pin, and a spring reacting against an element of said pin normally operative to keep said barrel-engaging element in operative relation to the barrel.

5. In combination with a tack and nail machine having cutting and forming tools and means for actuating them, an oscillatory barrel for guiding tack strip to the cutters, strip-feeding means carried by the barrel and means for oscillating the barrel, the strip-feeding means comprising a pair of rolls between which the strip passes on its way to the cutters, the top roll at least having movable bearings permitting the top roll to move bodily toward and from the other roll, and loading means for the top roll comprising a spring and a rocker device operative to transmit the spring pressure to the movable bearings of the top roll.

6. In combination with a tack and nail machine having cutting and forming tools and means for actuating them, an oscillatory barrel for guiding tack strip to the cutters, strip-feeding means carried by the barrel and means for oscillating the barrel, the strip-feeding means comprising a pair of rolls, one at least of said rolls being mounted in movable bearings whereby such roll is permitted to move bodily toward and from the other roll, a T-shaped rocker so arranged that the ends of its crossbar bear upon the respective bearings of the removable roll while the end of its stem rests upon a fixed support, and a loading spring bearing upon the stem of the rocker at a point between its free end and the crossbar.

7. In combination with a tack and nail machine having cutting and forming tools and means for actuating them, an oscillatory barrel for guiding tack strip to the cutters, strip-feeding means carried by the barrel and means for oscillating the barrel, the strip-feeding means comprising a pair of rolls between which the strip passes on its way to the cutters, the top roll at least being mounted in movable bearings whereby it may move bodily toward and from the other roll, and loading means for the top roll comprising a T-shaped rocker so arranged that end portions of its crossbar rest upon the respective movable bearings, the free end of the stem member of the rocker being rounded and resting upon a fixed support, the stem of the rocker being longitudinally slotted, and a loading element comprising a spring and a pin which is encircled by the spring and which passes through the slot in the stem member of the rocker, thereby permitting the rocker to be adjusted longitudinally with respect to the loading means.

8. In combination with a tack and nail machine having cutting and forming tools and means for actuating them, an oscillatory barrel for guiding tack strip to the cutters, strip-feeding means carried by the barrel and means for oscillating the barrel, the strip-feeding means comprising a pair of driven rolls between which the strip passes on its way to the cutters, one of said rolls having a substantially flat peripheral strip-contacting face and the other roll having a peripheral face of V-section providing a narrow edge for contacting with the strip.

9. In combination with a tack and nail machine having cutting and forming tools and means for actuating them, an oscillatory barrel for guiding tack strip to the cutters, strip-feeding means carried by the barrel and means for oscillating the barrel, a nose piece secured to the delivery end of the barrel, said nose piece being so attached to the barrel as to permit it to be

swung transversely of the barrel in planes substantially at right angles to each other.

10. In combination with a tack and nail machine having cutting and forming tools and means for actuating them, an oscillatory barrel for guiding tack strip to the cutters, strip-feeding means carried by the barrel and means for oscillating the barrel, a nose piece secured to the delivery end of the barrel, said nose piece comprising an elongate plate forming a support for the tack strip, and means operative to hold the strip substantially in contact with the plate as it moves along the latter, the plate having an integral bridge member adjacent to its delivery end, said bridge member having an elongate slot for confining and guiding the tack strip.

11. In combination with a tack and nail machine having cutting and forming tools and means for actuating them, an oscillatory barrel for guiding tack strip to the cutters, strip-feeding means carried by the barrel and means for oscillating the barrel, a nose piece secured to the delivery end of the barrel, said nose piece comprising an elongate plate forming a support for the tack strip, said plate having a fixed longitudinally slotted strip-guiding element adjacent to its end, and a resilient hold-down element operative to hold the tack strip substantially in contact with the plate as it moves along the latter, said hold-down strip being constructed and arranged for swinging movement laterally out of operative position to facilitate the introduction of a fresh strip into the nose piece.

12. In combination with a tack and nail machine having cutting and forming tools and means for actuating them, an oscillatory barrel for guiding tack strip to the cutters, strip-feeding means carried by the barrel and means for oscillating the barrel, a nose piece secured to the delivery end of the barrel, said nose piece comprising an elongate plate forming a support for the tack strip, a leaf spring pivotally secured near one edge of the plate and normally extending diagonally across the plate and overlying the tack strip to hold the latter substantially in contact with the plate, said spring being movable at will about its pivotal support to expose the strip to view.

13. In combination with a tack and nail machine having cutting and forming tools and means for actuating them, an oscillatory barrel for guiding tack strip to the cutters, strip-feeding means carried by the barrel and means for oscillating the barrel, a nose piece secured to the delivery end of the barrel, said nose piece comprising an elongate plate forming a support for the tack strip, said plate having apertures along the path of the strip to facilitate the discharge of lime from the nose piece, and an integral longitudinally slotted bridge member at its end operative to guide and confine the tack strip.

14. In combination with a tack and nail machine having cutters and forming tools, and means for actuating them, an oscillatory barrel for guiding tack strip on its way to the cutters, strip-feeding means carried by the barrel, and means for oscillating the barrel, a weighted lever normally tending to swing to upright position, and a feeler arm carried by the lever and normally engaging the tack strip on its way to the receiving end of the barrel thereby to hold the lever substantially horizontal so long as tack strip continues to enter the barrel.
